CLAIM

The ornamental design for a combined memorial holder and collection box, as shown and described.

DESCRIPTION

FIG. 1 is a top, front and left side perspective view of a combined memorial holder and collection box showing our new design;

FIG. 2 is a right side elevational view, the left side being a mirror image;

FIG. 3 is a rear elevational view;

FIG. 4 is a front elevational view of a second embodiment showing our new design;

FIG. 5 is a right side elevational view of a second embodiment of our new design of FIG. 4, the left side being a mirror image;

FIG. 6 is a top plane view thereof; and,

FIG. 7 is a rear elevational view thereof.

FIG. 1FIG. 2FIG. 3
